UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed February 14, 1921. Serial No. 444,663.

To all whom it may concern:

Be it known that I, TALBOT G. MARTIN, a citizen of the United States of America, and a resident of Chicago, Cook County, and 5 State of Illinois, have invented certain new and useful Improvements in Automatic Telephone Systems, of which the following is a specification.

The present invention relates in general to 10 automatic telephone systems, and is adapted to be used in a system of the multioffice type.

More specifically, the invention is adapted to be used in an automatic office wherein there are a number of trunks extending to 15 another automatic exchange. In such a system, in order to provide a large number of trunks extending to the second automatic exchange from one level of selector switches, outgoing secondary line switches are used.

20 If self aligning plunger type line switches are used in such a case, a certain difficulty manifests itself which is that the line switch may, under certain conditions, be plunged in on a busy trunk line. Self aligning line 25 switches are so constructed that immediately upon the release of the plunger arm after being operated, it assumes a position before the trunk line preselected by the associated master switch. In this arrangement there 30 is a short interval when the line switch is assuming this position during which if seized immediately it may plunge in on a busy trunk line. An object of the present invention, therefore, is to provide means for positively preventing the seizing of such a switch 35 until it has assumed its position in front of the preselected trunk line.

Another object of the invention is to provide means for rendering the trunk lines in 40 the selector level busy in case all the outgoing trunk lines in a group are in use.

The particular manner in which these and other results are accomplished will be described hereinafter reference being had to 45 the accompanying drawings in which Figs. 1 and 2 show by means of the usual circuit diagrams sufficient of the apparatus in an automatic telephone system to enable the invention to be explained and understood, 50 while Fig. 3 shows the mechanism of a self-aligning plunger.

Referring now to the drawings, in Fig. 1 is shown the usual automatic type of substation A having an individual line switch 55 C of the well known plunger type individual

thereto. The line switch C in common with a plurality of other line switches is adapted to be controlled by a master switch D. The function of the master switch D as is well known is to maintain the plungers of all 60 idle line switches opposite an idle trunk line. The trunk lines accessible to the line switch C and other similar line switches terminate in selector switches one of which is shown at E. The selector E is of the usual Strowger 65 vertical and rotary type having the usual set of 100 bank contacts arranged in ten rows or levels. Some levels of these selector switches lead to second selectors which in turn have access to connector switches. In 70 other levels of bank contacts are terminated trunk lines which extend to outgoing secondary line switches. The bank contacts 85—87, inclusive, accessible to the selector E terminate in the outgoing secondary line 75 switch C', Fig. 2.

The mechanical construction of the plunger arm of the line switch C' whereby the self aligning feature is secured is shown in Fig. 3. It will be seen that in place of the 80 usual slot in the fan of the plunger arm two arms 255 and 255' are used which are pressed into engagement with the guide on the master switch shaft 257 by the spring 258. When the line switch is operated the plunger arm guides 255 and 255' do not disengage the guide 256 on the master switch shaft. As the master switch operates seeking an idle trunk line the arm 255' is forced out of its 85 normal position by the guide on the master switch shaft. When the line switch is released the spring 258 causes the plunger arm to assume a position in front of the trunk line preselected by the master switch. Line 90 switches of this type are well known and their operation will be readily understood from the above description.

At G is shown the master switch which is associated with the line switch C' and a plurality of other outgoing line switches, whose function is to maintain the plungers of the line switches in front of an idle trunk line. The master switch G is of the usual solenoid type. As the mechanical construction and operation of the master switch of 100 this type is well known its operation will be but briefly explained hereinafter. The trunk lines to which the outgoing line switches similar to the line switch C' have 105 access lead to repeaters one of which is 110

shown at F. The repeater F is of the usual automatic type and constitutes the terminal of a trunk line extending to another automatic exchange.

Having briefly described the apparatus involved in the invention a detailed description of its operation will now be given. For this purpose it will be assumed that the subscriber at substation A desires to call a subscriber in another automatic exchange.

When the receiver is removed at substation A a circuit is completed for the line relay 20 over the line conductors 11 and 12 in series. Upon energizing, the line relay 20 at its armature 32 completes the circuit of the pull down winding 25. The pull down winding upon energizing, attracts the plunger arm 28 thereby forcing the springs 40-43, inclusive, into engagement with their working contacts. The cut off armature 29 is also attracted by the energization of the pull down winding 25. By the engagement of springs 40 and 43 with their working contacts the line conductors 11 and 12 are extended by way of armatures 70 and 73 and their back contacts to the upper and lower windings of the line relay 50 of the selector E.

The line relay 50 is energized over the line circuit of the calling subscriber and closes at its armature 60 the circuit of the slow acting release relay 51. The latter relay upon operating, at armature 62 prepares the operating circuits of the selector E and at armature 61 places ground on the release trunk conductor 63 thereby establishing a holding circuit which extends by way of working contact of spring 41 and the said spring, and through the holding winding 26 of the line switch C to battery. The energization of the holding winding 26 serves to maintain the cut off armature 29 and the plunger arm 28 in an operated position. It will be noted that the cut off armature upon operating opens the circuit of the line relay 20, and it will be understood that the circuit for the holding winding 26 was completed before the line relay 20 had time to deenergize. A branch of the holding circuit extends by way of the private normal conductor 39 to multiply connected test contacts in the banks of connector switches which have access to the line of the substation A whereby the said line is protected from intrusion in the well known manner.

By the engagement of spring 42 with its working contact ground is placed on the contact in the master switch bank associated with the selected trunk line whereby the master switch is caused to select another idle trunk line in the usual manner.

The calling subscriber at substation A may now operate his calling device for the first digit of his desired number. A series of interruptions are thereby produced in the

circuit of the line relay 50 which deenergizes a corresponding number of times. At each retraction of its armature 60 an impulse of current is sent over the following circuit: Ground by way of back contact and armature 72, armature 60 and its back contact, armature 62 and its front contact, winding of the slow acting series relay 52, and thence through the winding of the vertical magnet 55 to battery. Magnet 55 operates to raise the switch wipers 80-82, inclusive, step by step until they are placed opposite the level of bank contacts in which are terminated trunk lines leading to the outgoing secondary line switches. The slow acting relay 52 which is energized in series with the vertical magnet maintains its armature attracted throughout the vertical movement of the switch. Upon the first vertical step of the switch shaft a circuit is completed extending from ground on release trunk conductor 63, by way of armature 64 and its front contact, off normal spring 65 and its working contact, winding of the interrupter relay 53, working contact of spring 75 and the said spring, and back contact and armature 69 to battery. Upon energizing, relay 53 at armature 67 establishes a locking circuit for itself and at armature 68 prepares the rotary magnet circuit. Upon the termination of the vertical movement of the switch the slow acting relay 52 is deenergized and a circuit is completed extending from ground on release trunk conductor 63 by way of armature 64 and its back contact, armature 68 and its front contact, and through the winding of the rotary magnet 56 to battery. The rotary magnet 56 operates to rotate the switch wipers into engagement with the terminals of the first trunk line in the selected level and at the same time breaks the locking circuit of the interrupter relay 53 at armature 69. Relay 53 then deenergizes opening the circuit of the rotary magnet 56 which deenergizes also. The operation of the selector E now depends upon whether or not the trunk line with which the switch wipers 80-82, inclusive, are in engagement is or is not busy. If busy, there will be a ground potential present on the test contact engaged by test wiper 81 and a circuit may be traced extending from the said grounded test contact by way of test wiper 81, armature 71 and its back contact, off normal spring 65 and its working contact, through the winding of the interrupter relay 53, working contact of spring 75 and the said spring, and back contact and armature 69 to battery. The interrupter relay 53 is again energized over this circuit and operates in the same manner as before to establish a locking circuit for itself at armature 67 and at armature 68 to complete the rotary magnet circuit. Magnet 56 operates to rotate the switch wipers into engage- 120 125 130

ment with the bank contacts associated with the next trunk line in the selected level and to break the holding circuit of the interrupter relay 53 which deenergizes breaking the circuit of the rotary magnet which then deenergizes also. The alternate operation of the interrupter relay 53 and the rotary magnet 56 will continue until an idle trunk is found, which we will assume is the trunk line shown in the drawings terminating in bank contacts 85—87, inclusive. When this occurs there being no ground present on the test contact 86 engaged by test wiper 81 the switching relay 54 will be no longer short circuited. A circuit may then be traced extending from ground on release trunk conductor 63, through the winding of the switching relay 54, off normal spring 65 and its working contact, through the winding of the interrupter relay 53, working contact of spring 75 and the said spring, and back contact and armature 69 to battery. It may be stated at this point that the switching relay 54 is of comparatively high resistance and relay 53 will not operate over the above circuit.

The spring 75 is controlled by the double dog of the switch and hence when the release magnet operates the spring 75 is shifted out of engagement with its working contact. It will thus be noted that the spring 75 remains in engagement with its working contact as long as the switch is in an operated position, but is immediately forced out of engagement therewith by the operation of the release magnet.

Returning now to the operation of the selector E when the switching relay 54 is energized, upon operating, this relay at armatures 70 and 73 disconnects the incoming line conductors from the windings of the line relay and extends them by way of wipers 80 and 82, bank contacts 85 and 87, to the trunk conductors 90 and 92. Upon operating, relay 54 also extends ground by way of front contact and armature 71, test wiper 81, test contact 86, release trunk conductor 91, springs 109, armature 115 and its back contact, through the winding of the pull down winding 101 of the secondary line switch C', armature 215 and its back contact, armature 212 and its back contact, and thence through the winding of the slow acting relay 191 to battery. The pull down winding 101 and the slow acting relay 191 are energized over this circuit, relay 191 completing at its armature 211 a circuit of the peg count meter. The pull down winding 101, upon energizing, attracts the plunger arm 105 and the cut off armature 106. The plunger arm 105 forces the springs 110—113, inclusive, into engagement with their working contacts. By the engagement of springs 110 and 113 with their working contacts the incoming trunk conductors

90 and 92 are extended by way of normally closed springs controlled by armatures 160 and 162 through the upper and lower windings of the line relay 151 of the repeater F.

The line relay 151 is energized over the calling subscriber's line loop and closes at its armature 165, a circuit of the slow acting release relay 152. The latter relay upon energizing, prepares the repeating circuit at 75 armature 169, at armature 171 completes a circuit of the polarizing winding of the polarized relay 154, and at armature 170 places ground on release trunk conductor 179 thereby establishing a holding circuit 80 which extends by way of working contact of spring 111 and the said spring, working contact of spring 108 and the said spring, winding of the slow acting relay 100, and through the holding winding of the line 85 switch C' to battery. The operation of relay 100, however, is without function at this time. The holding winding 102 upon energizing, maintains the cut off armature 106 and the plunger arm 105 in their operated 90 positions. A branch of this holding circuit also extends by way of the release trunk conductor 91, bank contact 86, test wiper 81, armature 71 and its front contact, where it divides one path extending back to the holding winding of the line switch C, the other through the winding of the switching relay 54 of the selector E. This circuit serves to maintain the switches C, E, and C' in 95 their operated positions.

By the engagement of spring 112 with its working contact a circuit is completed by way of master switch wiper 235, conductor 230, and through the winding of the starting relay 193 to battery. Relay 193 completes a circuit extending from ground through the low resistance winding of relay 192 by way of front contact and armature 216, through the winding of the locking magnet 196, and thence by way of back contact and armature 210 to battery. The locking magnet 196 energizes over this circuit and at armature 225 and its front contact completes a circuit for the high resistance winding of relay 192. Relay 192 will be energized over this circuit and at armature 213 will complete the circuit of the lamp L in series with a slow acting alarm. This provision is made so that should anything go wrong with the master switch the alarm will come in and the exchange attendant may at once find the trouble. The locking magnet 196 also withdraws the locking pawl from the master switch segment thereby causing the master switch to rotate under influence of its spring in search of an idle trunk line. When the master switch wiper 235 engages the bank contact of an idle trunk line the starting relay 193 is deenergized 100 and immediately opens the circuit of the 105

locking magnet 196 which allows the locking pawl to again engage the locking segment.

It will be noticed that a branch of the holding circuit extends through the winding 5 of the chain relay 200 to battery. Relay 200 upon operating, at armature 241 completes one point in the chain. Should all the trunks of a group happen to be busy all the chain relays similar to relays 200, 201 and 10 202 will be energized and a circuit will be completed for the stop relay 190. A branch of this circuit also extends to another meter which thus registers each time all trunks become busy. The relay 190 upon energizing, removes battery from the locking magnet 196, from the solenoid 227 and the trip relay 195 of the master switch G thus preventing the master switch from rotating under these conditions. As all trunks are 15 busy there will be a ground present on the bank contact engaged by the master switch wiper 235 and the start relay 193 will be energized. Ground is thus placed by way of the pull down windings of the secondary 20 line switches on the release trunk conductors extending back to the selector switches similar to E whereby the selectors are prevented from seizing these trunk lines. As soon as 25 any one of the trunks become idle the associated chain relay is deenergized and the circuit of the stop relay 190 is opened at this point. The relay 190 immediately deenergizes again extending battery to the master switch which operates to select the trunk 30 35 which has become idle.

The calling subscriber may now operate his calling device for the next digit of the desired subscriber's number. A series of interruptions are thereby produced in the 40 circuit of the line relay 151 of the repeater F which retracts its armatures a corresponding number of times. At each retraction of its armature 165 an impulse of current is sent to the slow acting relay 153. When the 45 line relay was first energized a bridge was placed across the trunk conductors 180 and 181. This bridge extends by way of armature 169 and its front contact, armature 175 and its back contact, upper winding of the 50 polarized relay 154, normally closed springs controlled by armature 163, right hand winding of the impedance coil 155, armature 166 and its front contact, to trunk conductor 181. The line relay of the incoming selector 55 in the other automatic exchange is energized over this circuit and completes a circuit of its associated slow acting release relay. Returning now to the operation of the repeater 60 F when the second digit of the called subscriber's number was sent, the relay 153 energizes and removes one winding of the polarized relay 154 and the winding of the impedance coil 155 from the bridge across 65 the trunk conductors thus closing a good repeating circuit. It will be seen that after

each operation of the calling device at substation A a series of interruptions will be produced in the line relays of the switches in the other automatic exchange and they will be operated in the usual manner to extend a connection to the desired called subscriber. When the receiver is removed at the called substation the back bridge relay of the connector switch used in the connection is operated and serves to reverse the 70 polarity of the battery supplied to the trunk conductors 180 and 181. The polarized relay 154 in the repeater E immediately operates completing the circuit of the reversing relay 150 at armature 177 and completing the talking connection. Relay 150 operates to reverse the battery back to the calling subscriber's line in order to operate a meter or for any desirable purpose and at armature 163 places both windings of the impedance coil 155 across the bridge of the trunk conductors thus materially improving the transmission. The calling and called subscribers may now converse with each other battery being supplied to the calling subscriber from the windings of the line relay 151 of the repeater F, and to the called subscriber from the windings of the back bridge relay in his associated connector switch.

When the conversation is terminated the calling subscriber at substation A by replacing his receiver upon the switchhook will cause the deenergization of the line relay 151 of the repeater F which immediately deenergizes breaking the circuit of the slow acting release relay 152. The latter relay will deenergize after a short interval breaking the circuit of the line relay of the connector switch which is in the distant exchange and removing ground from the release trunk conductor 179. When ground is removed from the release trunk conductor 179 the associated chain relay 200 is deenergized as is the holding winding 102 of the outgoing secondary line switch C' and the switching relay 54 of the selector E and the holding winding of the individual line switch C. Upon the deenergization of the holding winding of the line switch C the plunger arm and the cut off armature immediately assume their normal positions.

When the switching relay 54 deenergizes the circuit of the release magnet 57 is completed and the switch is restored to its normal position. By the operation of the release magnet 57 the spring 75 is opened. It will now be apparent that should the test wiper 81 of the selector E engage on grounded test contacts upon its release there will be no circuit completed for the interrupter relay 53 as this circuit is opened by the operation of spring 75. Thus the relay 53 will not again energize and interfere with the release of the selector switch.

The holding winding 102 of the line switch C', upon deenergizing, allows the cut off armature 106 and the plunger arm 105 to immediately restore to normal position. The circuit of the slow acting relay 100 is broken as soon as ground is removed from the release trunk conductor 91 but as this relay is slow acting it will not immediately retract its armature. Ground is thus again placed on the release trunk conductor 91 as soon as the cut off armature 106 of the line switch C' restores to normal. The slow acting relay 100 is slow enough to retract its armatures so that ground is maintained on release trunk conductor 91 until the plunger arm of the line switch C' has assumed its position before the trunk line preselected by the associated master switch G. The ground on release trunk conductor 91 prevents another selector switch having access to this trunk line from selecting the line switch C' for use until it has assumed its position before an idle trunk line.

In the above manner all the switches operated in the connection are restored to normal position.

Having fully described and ascertained the features of the invention what is considered to be new and desired to have protected by Letters Patent will be pointed out in the appended claims.

What I claim as my invention is:

1. In a telephone system, a trunk line terminating in a self aligning line switch, trunk lines accessible to said line switch, means for seizing said first trunk line and operating said line switch to seize one of said second trunk lines, means for causing said line switch, when released, to assume a position before another idle trunk line, and means operative while said switch is assuming its position for applying the busy potential to said first trunk line.

2. In a telephone system, a trunk line terminating in a self aligning line switch, trunk lines accessible to said line switch, means for seizing said first trunk line and operating said line switch to seize one of said second trunk lines, means for causing said line switch, when released, to assume a position before another idle trunk line, and a relay energized while said switch is assuming its position for applying the busy potential to said first trunk line.

3. In a telephone system, selector switches, trunk lines accessible to said selector switches terminating in line switches, trunk lines accessible to said line switches, means for operating one of said line switches to seize one of said second trunk lines, means for restoring said line switch to normal, and means operating while said switch is being restored to normal for applying busy potential to the associated trunk line.

4. In a telephone system, selector switches,

trunk lines accessible to said selector switches terminating in line switches, trunk lines accessible to said line switches, means for operating one of said line switches to seize one of said second trunk lines, means for releasing said line switch, and a relay operated while said switch is being released for applying a busy potential to the associated trunk line.

5. In a telephone system, selector switches, trunk lines accessible thereto terminating in the self aligning line switches, trunk lines accessible to said line switches, means for operating one of said selector switches to seize one of said first trunk lines, and for then operating the associated line switch to seize one of said second trunk lines, means for causing said line switch when released to assume a position before another idle one of said second trunk lines, and means operative while said switch is assuming its position for applying a busy potential to the associated trunk line in all of said selector switches.

6. In a telephone system, groups of selector switches, line switches, trunk lines accessible to one group of said selector switches and terminating in said line switches, trunk lines terminating in said other group of selector switches and accessible to said line switches, means for seizing the selector switches of one group to cause the seizure of the selector switches of the other group through the medium of certain of said line switches, means responsive when all the selectors of the second group have been seized for making the line switches busy to all selectors of the first group, means for releasing selectors of the second group to cause the release of the particular line switches used, and means in said line switches for making their associated trunks busy during such release.

7. In a telephone system, a selector switch, a line switch, means operable to cause said selector to seize said line switch, means responsive to such seizure for causing said line switch to seize a trunk terminating in a second selector switch, means in said second selector for maintaining said first selector and said line switch in an operated position and to make said line switch busy to other first selector switches, means for releasing said switches, and means operated when the line switch was seized and effective when the release is initiated for maintaining its associated trunk busy during its releasing operation.

8. In a telephone system, a selector switch, a line switch, means operable to cause said selector to seize said line switch, means responsive to such seizure for causing said line switch to seize a trunk terminating in a second selector switch, means in said second selector for maintaining said first selector

- and said line switch in an operated position and to make said line switch busy to other first selector switches, means for releasing said switches, means operated when the line 5 switch was seized and effective when the release is initiated for maintaining its associated trunk busy during its releasing operation, and means for causing said line switch, when released, to assume a position before an 10 idle trunk line.
9. In a telephone system, trunk lines terminating in line switches, other trunk lines, a master switch for maintaining said switches in position before an idle one of said other 15 trunk lines to which said line switches have access, means associated with said last trunk lines for maintaining the first trunk lines busy when their respective switches are in an operated position, and means associated 20 with said switches for maintaining their associated trunks busy during the time required for restoring said switches and for positioning them before the next idle trunk.
10. In a telephone system, trunk lines terminating in line switches, other trunk lines adapted to be seized by said line switches, a master switch for maintaining all idle switches in position before an idle trunk line to which said line switches have access, 25 means associated with said last trunk lines for maintaining the first trunk lines busy while their associated switches are operated, means for releasing said switches, and means associated with said switches for maintaining 30 their associated trunks busy during the time required for their restoration to normal.
11. In a telephone system, means including two directive switches for connecting a calling and called line, the connection also 35 including a non-directive switch inserted between said directive switches, means for causing said non-directive switch to select another directive switch when the connection is released, and means for rendering said 40 non-directive switch busy while such selecting operation is taking place.
12. In a telephone system, first selectors, secondary line switches, and second selectors, means for operating a switch of each kind, 45 to establish a connection, means for automatically operating the secondary switch in use when the connection is released in order to pre-select a second selector for the next call, and means for making such secondary switch busy to said first selectors while the 50 pre-selecting operation is taking place.
13. In a telephone system, first selectors, secondary line switches, and second selectors, means for operating a switch of each kind to 55 establish a connection, a master switch for causing the other secondary switches to select an idle second selector when the secondary switch in use is operated, means for causing said last mentioned secondary switch 60 to select the same idle second selector when the connection is released, and means for making such secondary switch busy to said first selectors until its selecting operation is completed.
14. In a plunger line switch, a holding coil for retaining said switch in operated position, a pair of contacts held open while said coil is energized, a slow acting relay connected in circuit with said coil and energized at the same time, a second pair of contacts held closed by said relay when the same is in energized position, and a circuit for making said switch busy including both pairs of contacts in series. 70
15. In a telephone system, a trunk line including a combined test and holding conductor and terminating in a self aligning line switch, trunk lines accessible to said line switch, means for seizing said first trunk line and for operating said line switch to seize one of said second trunk lines, means for applying a potential to said combined holding and test conductor to hold said line switch operated and to maintain the first named trunk line in a busy condition, means for releasing said line switch by removing said potential, means for causing said line switch, when released, to assume a position before another idle trunk line, and means operative while said switch is assuming its new position for applying a busy potential to said combined test and holding conductor to maintain the trunk line busy. 80
16. In a telephone system, a trunk line including a combined test and holding conductor and terminating in a self aligning line switch, trunk lines accessible to said line switch, means for seizing said first trunk line and for operating said line switch to seize one of said second trunk lines, means for applying a potential to said combined holding and test conductor to hold said line switch operated and to maintain the first named trunk line in a busy condition, means for releasing said line switch by removing said potential, means for causing said line switch, when released, to assume a position before another idle trunk line, a circuit for applying a busy potential to said combined test and holding conductor, and means for closing said circuit responsive to the removal of the busying and holding potential and for again opening it after the switch has assumed its new position. 90
17. In a telephone system, a trunk line including a combined test and operating conductor and terminating in a self aligning line switch, trunk lines accessible to said line switch, means for seizing said first trunk line and for operating said line switch over said conductor to seize one of said second trunk lines, means for applying a potential to said combined operating and test conductor to maintain the first named trunk line in a busy condition, means for removing said 100
18. In a telephone system, a trunk line including a combined test and holding conductor and terminating in a self aligning line switch, trunk lines accessible to said line switch, means for seizing said first trunk line and for operating said line switch to seize one of said second trunk lines, means for applying a potential to said combined holding and test conductor to hold said line switch operated and to maintain the first named trunk line in a busy condition, means for releasing said line switch by removing said potential, means for causing said line switch, when released, to assume a position before another idle trunk line, a circuit for applying a busy potential to said combined test and holding conductor, and means for closing said circuit responsive to the removal of the busying and holding potential and for again opening it after the switch has assumed its new position. 110
19. In a telephone system, a trunk line including a combined test and operating conductor and terminating in a self aligning line switch, trunk lines accessible to said line switch, means for seizing said first trunk line and for operating said line switch over said conductor to seize one of said second trunk lines, means for applying a potential to said combined operating and test conductor to maintain the first named trunk line in a busy condition, means for removing said 120
20. In a telephone system, a trunk line including a combined test and holding conductor and terminating in a self aligning line switch, trunk lines accessible to said line switch, means for seizing said first trunk line and for operating said line switch to seize one of said second trunk lines, means for applying a potential to said combined holding and test conductor to hold said line switch operated and to maintain the first named trunk line in a busy condition, means for releasing said line switch by removing said potential, means for causing said line switch, when released, to assume a position before another idle trunk line, a circuit for applying a busy potential to said combined test and holding conductor, and means for closing said circuit responsive to the removal of the busying and holding potential and for again opening it after the switch has assumed its new position. 125
21. In a telephone system, a trunk line including a combined test and operating conductor and terminating in a self aligning line switch, trunk lines accessible to said line switch, means for seizing said first trunk line and for operating said line switch over said conductor to seize one of said second trunk lines, means for applying a potential to said combined operating and test conductor to maintain the first named trunk line in a busy condition, means for removing said 130

potential and for releasing said line switch, means for causing said line switch when released to assume a position before another idle trunk line, a circuit for applying a busy potential to said combined test and operating conductor, means for closing said circuit during the release of said switch and for again opening it after the switch has assumed its new position, and means for preventing the application of the busy potential to the combined test and operating conductor during the release of the switch from reoperating the same.

18. In a telephone system, a trunk line including a combined test and operating conductor and terminating in a self aligning line switch, trunk lines accessible to said line switch, means for seizing said first trunk line and for operating said line switch to seize one of said second trunk lines, means for applying a potential to said combined operating and test conductor to maintain the first named trunk line in a busy condition, means for removing said potential and for releasing said line switch, means for causing said line switch when released to assume a position before another idle trunk line, a circuit for applying a busy potential to said combined test and operating conductor, means for closing the busying circuit during the release of the switch and for preventing the application of the busy potential to the

combined holding and test conductor at such time from reoperating the switch.

19. In a telephone system, a trunk line 35 including a combined test and operating conductor and terminating in a self aligning line switch, trunk lines accessible to said line switch, means for seizing said first trunk line and for operating said line switch to 40 seize one of said second trunk lines, means for applying a potential to said combined operating and test conductor to maintain the first named trunk line in a busy condition, means for removing said potential and for 45 releasing said line switch, means for causing said line switch when released to assume a position before another idle trunk line, a circuit for applying a busy potential to said combined test and operating conductor, 50 means for closing the busying circuit during the release of the switch and for preventing the application of the busy potential to the combined holding and test conductor at such time from reoperating the switch, 55 and means operative after the switch has assumed its new position for removing the busying potential from said combined holding and test conductor and for preparing the switch for reoperation over such conductor. 60

Signed by me at Chicago, Cook County, Illinois, this 1st day of February, 1921.
